MOP

Edward H. Tate, Malden, Mass.

Application April 14, 1933, Serial No. 666,139

4 Claims. (Cl. 15—147)

This invention relates to improved mop structure resulting in a mop which is light but strong and economical to manufacture. Mops embodying the invention are characterized by simplicity and rigidity of structure so that although they are light in weight and easy to handle, they are strong and durable. Such a mop consists primarily of a handle, a pair of brackets and a cleaning element revolvably mounted between the brackets. These brackets are preferably reinforced for rigidity and may be further strengthened by a rod which is rigidly attached at its ends to the end portions of the respective brackets, the cleaning element being adapted to revolve freely on the rod between the brackets so as to present different faces to the surface to be cleaned.

For a more complete understanding of the invention reference may be had to the description thereof which follows and to the drawing of which

Figure 1 is a perspective view of a mop embodying the invention.

Figure 2 is a fragmentary view partly in section of a portion of Figure 1.

Figure 3 is a perspective view of the mop structure without the cleaning element.

Figure 4 is a fragmentary view showing a detail of structure.

Figure 5 is a similar view of a modified detail of structure.

Figure 6 is a view similar to Figure 2 but showing a modified structure.

Figure 7 is a perspective view of a mop structure including the modified details shown in Figures 5 and 6.

The mop may comprise a handle 10 of any suitable length to the lower end portion of which are secured a pair of laterally projecting brackets 11 and 12. These brackets have parallel portions 13 and 14 disposed against opposite sides of the lower end portion of the mop handle and secured thereto as by suitable bolts 15, and laterally extending portions, preferably reinforced by a strap 20 which, as shown, may be riveted or otherwise permanently secured thereto. The strap connects the brackets rigidly together so that the bolts 15 are not depended upon to maintain the brackets in position relative to each other but serve only to attach the brackets to the handle 10. The brackets 11 and 12 have their free end portions 25 which, as shown in Figure 4, may be provided with non-circular perforations 26. A rod 30 extends between the end portions 25 of the brackets, this rod having reduced end portions 31 fitting the perforations 26 forming shoulders

32 which rest against the opposing faces of the respective end portions 25 of the brackets. The reduced portions 31 project through the perforations 26, the projecting portions being peened against the outer faces of the brackets as indicated at 33 in Figure 2. This results in a second shoulder at each end of the rod 30 which bears against the outer face of the respective bracket. It is evident that by such structure the rod is permanently and rigidly secured to the end portions 10 of the bracket so that relative motion of any kind between the rod and the brackets is positively prevented. The rod furthermore acts as a stiffening member for the brackets. Thus I may employ light-weight flat bar stock to produce a 15 strong, stiff mop frame. It is evident from Figure 3 that the rod 30 and the reinforcing member 20 combine with the brackets 11 and 12 to form a permanent rigid loop which cannot be distorted in the ordinary use of the mop and is fitted to 20 withstand hard usage.

When a mop is being assembled, a cleaning element is mounted on the rod 30 before it is secured to the brackets. This cleaning element, as indicated in Figure 1, may be in the form of a 25 loop 40 of inter-twisted wires, suitable textile strands 41 or other equivalent mop material being caught and gripped between the wires as shown. At diametrically opposite points of the loop, the wires are spread as at 43 to form a pair 30 of apertures through which the rod 30 can extend loosely. Thus when the mop is assembled, the loop 40 is freely revoluble on the fixed rod 30 so that either face of the cleaning element may be presented to the work.

Instead of the rod 30 extending from the end of one bracket to the end of the other, I may employ a pair of rod portions or pins 50, these being permanently secured to the ends 25 of the brackets and projecting inwardly therefrom on 40 a common axis. Each pin 50 may be provided with an element 51 forming a shoulder to fit against the inner face of the end portion 25a of one of the brackets. The end of the pin projecting through the bracket is preferably peened 45 over as shown at 52 in Figure 6, forming a second shoulder bearing against the outer face of the bracket. The portion of the pin extending through the bracket engages in a non-round hole 53 in the bracket, this portion of the pin being 50 either originally shaped to fit the hole or deformed into locking shape by the peening operation.

A cleaning element similar to that shown in Figure 1 may be employed with this form of mop,

the loop 40 revolving freely on the pins 50. As the loop 40 is somewhat resilient, the sides can be sprung inwardly a sufficient distance to clear the end of one of the pins 50 so that the cleaning element can easily be detached from the brackets if desired.

It is evident that the invention herein described is capable of various modifications without departing from the spirit or scope thereof as defined by the following claims.

I claim:

1. A mop having a handle, a pair of brackets projecting laterally and downwardly from said handle, a reinforcing member extending across the end of said handle and secured to both said brackets, a rod having its ends permanently and rigidly secured to respective end portions of said brackets, and a cleaning element loosely mounted on said rod between said brackets to revolve thereon.

2. A lamp having a handle, a pair of brackets projecting laterally and downwardly from said handle, a rod having its ends permanently and rigidly secured to the end portions of the respective brackets against movement of any kind relative thereto, and a cleaning element loosely

mounted on said rod between said brackets to revolve thereon.

3. A mop having a handle, a pair of brackets projecting laterally and downwardly from said handle, a reinforcing member extending across the end of said handle and permanently secured to each of said brackets at two spaced points, a rod having its ends permanently and rigidly secured to the end portions of the respective brackets, and a cleaning element loosely mounted on said rod between said brackets to revolve thereon.

4. Mop structure comprising a handle, a pair of brackets, extending laterally and downwardly from said handle and provided with noncircular apertures through their free end portions, and a rod having reduced end portions forming shoulders engaging the opposing faces of said brackets adjacent to said apertures, said reduced portions fitting in said apertures to prevent rotation of said rod, and projecting therethrough, the projecting end portions of the rod being peened against the outer faces of the brackets whereby the rod is rigidly and permanently secured to said brackets.

EDWARD H. TATE.
